United States Patent Office

Des. 223,205
Patented Mar. 28, 1972

223,205

DRESSER OR THE LIKE

Joseph E. Atkinson, 3807 Leland St.,
Chevy Chase, Md. 20015

Filed Apr. 20, 1970, Ser. No. 22,525

Term of patent 7 years

Int. Cl. D6—04

U.S. Cl. D33—6

FIG.2

FIG.1

FIG. 1 is a view in perspective of the dresser.

FIG. 2 is a view of the right-hand end of the dresser of FIG. 1.

The side of the article not shown is a mirror image of the side shown while the back is plain and unornamented.

I claim:

The ornamental design for a dresser or the like, substantially as shown and described.
